FREQUENCY CONTROL

Carl Fichandler, New York, N. Y.

Application October 5, 1931, Serial No. 567,120

18 Claims. (Cl. 179—171)

This invention relates broadly to methods of varying alternating current circuit impedances and to the applications of said methods for frequency modulation and control.

5 Heretofore, frequency modulation has been accomplished usually by varying the capacity of a condenser in a resonant oscillating circuit in accordance with the signal impulse. This system of modulation is not satisfactory because the low frequency signal circuit is linked electrically and mechanically to the high frequency circuit, whereas said circuits should be separate. For example, in a radio-telephone system, it is absolutely necessary to locate the voice input dis-
10 tantly of the radio transmitter, and for this reason it is customary to convert the voice signals into electrical impulses by means of a microphone, and after conducting said electrical impulses to the transmitter, to reconvert them into
15 mechanical impulses thereby to activate the oscillating condenser through the medium of electro-mechanical means, such as a loud-speaker. Remote control for radio telegraphy has been accomplished by the use of a relay, the armature of
20 which activates a variable condenser. Mechanical devices thus employed for remote control in radio-telephony are undesirable, more particularly because the stiffness and inertia of said devices cause distortion; and such devices are
25 impractical for signals of a very high frequency, such as television signals for example.

35 An object of the present invention, therefore, is the provision of means for and a method of modulating the frequency of signals solely by electrical means having no moving parts.

Existing means for frequency modulation are unsatisfactory also because they produce undesired amplitude modulation.

40 Another object of this invention, therefore, is the provision of means for and a method of modulating frequency and eliminating amplitude variations.

45 A further object of the invention is an improved method of varying the total effective resistance of an alternating current circuit containing predominantly resistive and predominantly reactive elements.

50 A further object of the invention is an improved method of frequency modulation in a crystal-controlled oscillator circuit.

A still further object is generally to improve the art of frequency modulation.

The invention according to which the above objects are realized can best be understood from the following description considered in connection with the accompanying drawing, in which:

60 Figures 3 and 4 illustrate the embodiments of

the invention in two oscillator circuits of different types;

Figure 5 illustrates the embodiment of the invention in a remote controlled frequency modulated telephone circuit:

Figure 6 is the equivalent electrical circuit of a control crystal and its mounting;

Figure 7 is a radio-telegraphy circuit with crystal control and frequency modulation;

Figure 8 shows an arrangement for frequency modulation in a telegraph transmitter by movement of the crystal mounting-plate.

The present invention, which provides means for frequency modulation by purely electrical means as well as for eliminating disturbing amplitude variations, is based upon the following principles: 15

If, in an electrical alternating current circuit a variable resistance and a fixed reactance (capacitance or inductance) are connected in parallel, as illustrated by Figure 1, *a* and *b*, the values of which, using complex symbols, are x and jy , respectively, the total circuit impedance Z of the network equals:

$$Z = \frac{xy}{x+iy} = \frac{xy^2 + jx^2y}{x^2 + y^2} \quad \text{Eq. 1}$$

The real, or resistive component, Z_r , of Z is:

$$Z_r = \frac{xy^2}{x^2 + y^2} \quad \text{Eq. 2-30}$$

and the imaginary, or reactive component, Z_i , of Z is:

$$Z_i = \frac{x^2 y}{x^2 + y^2} \quad \text{Eq. 3 35}$$

If these impedance components of the parallel circuit network are drawn as functions of the variable resistance x , (using, if desired, the fixed impedance y as unit of the scale), as shown in Fig. 2, *e* and *f*, in which the abscissæ represent the variable resistance, x ; the ordinates, the resistive and the reactive components of the combined circuit impedance, Z_r and Z_i , respectively, we find that the resistance component first increases, reaches the maximum $y/2$, when x equals y , and then decreases towards the value zero, which it reaches when x equals infinity. The corresponding reactance component steadily increases, passes the value $y/2$ at its maximum rate of change, when x equals y , and keeps on increasing towards its ultimate value y , when x equals infinity. In the neighborhood of the values $x=y$,

the differential of Z_r with respect to x equals zero, which means that a small change of x produces practically no change in the resistive component of circuit impedance. The differential of Z_i with respect to x , in the same neighborhood, equals one-half, which means that a small change of x produces a relatively considerable change in the

reactive component of circuit impedance; this change being equal to one-half of the change of x .

Conversely, it can similarly be shown that if near the value $x=y$, we vary the reactive member 5 of the parallel connection slightly, the net effect on the total circuit impedance is not a change of the reactive, but of the resistive component. The resistive component of the circuit impedance is as given by above Eq. 2:

10

$$Z_r = \frac{xy^2}{x^2+y^2}$$

and in order to find the effect of a small change in y , we differentiate the above equation with respect to y , as set forth in the following equation:

$$\frac{dZ_r}{dy} = \frac{2yx^3}{(x^2+y^2)^2}$$

20 For the case that $y=x$ we find:

$$\frac{dZ_r}{dy} = \frac{1}{2}$$

which shows a definite effect upon the resistive 25 impedance component. Now, in order to find the effect on the reactive component represented by above Eq. 3 as

30

$$Z_i = \frac{x^2y}{x^2+y^2}$$

we differentiate this equation with regard to y , finding

35

$$\frac{dZ_i}{dy} = \frac{x^4 - x^2y^2}{x^2 + y^2}$$

For the case that $y=x$, we find:

$$\frac{dZ_i}{dy} = 0$$

40 showing that the differential disappears, i. e., a small change of y has no effect upon the reactive impedance component.

A further inversion of the above principle is obtained by connecting the resistive member and the reactive member in series, as shown in Figure 1, c and d. In this circuit connection, all statements above made for resistance in the parallel connection, are now valid for conductance; all statements made for capacitive or inductive resistance are valid for admittance or susceptance. Thus, in parallel networks as illustrated, for example in Fig. 1, a and b, the network impedance=

55

$$Z_p = \frac{xy}{x+y}$$

In series circuits, illustrated in Fig. 1, c and d, the impedance $Z_s = x+y$, and the network admittance=

60

$$G_s = \frac{1}{Z_s} =$$

$$\frac{1}{x+y} = \frac{\frac{1}{x} \cdot \frac{1}{y}}{\frac{1}{x} + \frac{1}{y}} = \frac{G_x G_y}{G_x + G_y}$$

65 which is of exactly the same form as the above equation,

70

$$Z_p = \frac{xy}{x+y}$$

From this formal identity it becomes clear that any relation derived between the impedances of parallel networks and the impedances of their

component elements are valid for the relations between the admittances of the reciprocal series networks and the admittances of their component elements.

As shown in Figure 3, the present invention 5 is embodied in a Hartley oscillator circuit which, as here shown, comprises the thermionic vacuum tube 11, the anode battery 12, the cathode battery 13, the oscillator tuning condenser 14, the oscillator tuning coil 15, the circuit resistance 10

16, and auxiliary or modulating condenser 17 and a variable modulating resistor 18. The vacuum tube 11 may be regarded as a negative resistance, the value of which is essentially a function of the amplitude of oscillation. This 15 amplitude adjusts itself so that the negative tube resistance is just large enough to compensate for the positive circuit damping resistance 16 and for the resistive component of the modulating network comprising the condenser 17 and the modulating resistor 18. On the basis of the preceding 20 discussion it can be shown that if the resistance, r , of the modulating resistor 18 approximately equals the reciprocal of the capacity of condenser 17 multiplied by the circular frequency of the 25 oscillator, w , then a small change, dr , of the modulating resistance, r , produces a change in the effective capacitive impedance component of network 17, 18 of the magnitude

30

$$dy = \frac{dr}{2}$$

whereas the corresponding change in resistive impedance component equals

35

$$\frac{(dr)^2}{4r}$$

which is small to the second order. Consequently, 40 the amplitude variation produced by the change in modulator resistance is negligible, compared to the frequency variation caused by the above change of modulator capacity. This is shown as follows:

The impedance (Z) of network 17, 18=

$$R \cdot \frac{1 - RCjw}{1 + R^2C^2w^2}$$

where R =resistance of 18; and C =capacity of 17. 50

$$x = \frac{R}{1 + R^2C^2w^2}$$

$$y = \frac{R^2Cw}{1 + R^2C^2w^2}$$

$$dy = dR \cdot \frac{2RCw}{(1 + R^2C^2w^2)^2}$$

for

$$R = \frac{1}{Cw}$$

$$dy = \frac{dR}{2}$$

$$dx = \frac{1 - R^2C^2w^2}{(1 + R^2C^2w^2)^2} dR$$

60

$$R = \frac{1}{Cw}$$

$$\frac{dx}{dR} = 0$$

For finite variations, resorting to the second dif- 75

ferential, since in accordance with Taylor's series

$$\Delta x = \Delta R \frac{dx}{dR} - \frac{1}{2}(\Delta R)^2 \cdot \frac{d^2x}{dR^2}$$

$$\frac{d^2x}{dR^2} = -\frac{4RC^2w^2}{(1+R^2C^2w^2)^2}$$

for

$$R = \frac{1}{Cw}$$

$$\frac{d^2x}{dR^2} = -\frac{1}{2R}$$

consequently,

$$\Delta x = \frac{1}{2} \Delta R \cdot \frac{d^2x}{dR^2} = \frac{(\Delta R)^2}{4R}$$

The above formula, impedance (Z) of network 17, 18 =

$$R \cdot \frac{1 - RCjw}{1 + R^2C^2w^2}$$

is derived as follows: According to the above Eq. 1,

$$Z = \frac{xy^2 + jx^2y}{x^2 + y^2}$$

which may be rewritten as

$$Z = xy \cdot \frac{y + jx}{x^2 + y^2}$$

Substituting R for x and

$$\frac{-1}{Cw}$$

for y,

$$Z = \frac{R}{Cjw} \cdot \frac{-\frac{1}{Cw} + jR}{R^2 + \frac{1}{C^2w^2}}$$

$$= R \cdot \frac{j + RCw}{1 + R^2C^2w^2}$$

$$= R \cdot \frac{1 - RCjw}{1 + R^2C^2w^2}$$

Figure 4 illustrates the application of the invention to a Meissner type of oscillator. This oscillator comprises the thermionic vacuum tube 21, a plate battery 22, a filament battery 23, an oscillator tuning coil 24, an oscillator tuning condenser 25, a feed-back coupling coil 26, an auxiliary or modulating inductance 27 and a varying modulating resistor 28. The action of the modulator comprising the inductance 27 and resistor 28 is the equivalent of the modulating condenser 17 and modulating resistor 18 of the circuit shown in Figure 3, the difference being mainly that in the circuit, shown in Figure 4, inductance is used instead of capacity and a series connection of resistance and reactance is employed instead of a parallel connection.

As shown in Figure 5, the invention is applied to the remote control of a frequency modulated radio telephony circuit, and as described in connection with Figures 3 and 4, the modulation is accomplished by resistance change. In order to produce this resistance change by remote control and solely by electrical means, there is here utilized the principle that the plate resistance of a thermionic tube varies with the grid voltage. As here shown, the circuit comprises a microphone 31, a battery 32, an audio frequency circuit transformer 33, a modulating tube 34, a radio frequency choke coil 35, plate battery 36, a fila-

ment battery 37, a radio frequency coupling condenser 38, a radio frequency grid tuning condenser 39, a radio frequency grid tuning coil 40, a radio frequency oscillator tube 41, a plate battery 42, a filament battery 43, a radio frequency plate tuning condenser 44, radio frequency plate tuning coil 45, a compensating resistance 46, a compensating coil 47 and a compensating condenser 48. The micro-phone 31 and the battery 32 may be remote from the radio frequency circuit and may be connected to the primary of the transformer 33 by a line of arbitrary length. In operation, the current variations produced by the micro-phone 31 are transmitted to the primary of the transformer 33 and through the medium of the secondary of the transformer corresponding voltage impulses are impressed on the grid of modulator tube 34, producing corresponding changes in its plate resistance. The choke coil 35 has a very high impedance, compared to the plate resistance, and prevents the plate battery 36 from forming a low resistance by-pass for radio frequency oscillations. The modulator tube 34 is coupled to the radio frequency circuit by the small condenser 38 which has an impedance at the oscillator frequency approximately equal to the plate resistance of tube 34. As previously explained, the modulator produces on the circuit a resistive effect, which, although small, is proportional to the square of the modulator resistance change. In high quality circuits it is desirable to compensate for even this small resistive effect. For this purpose the network comprising the compensating resistance 46, connected in parallel with the compensating inductance 47 and the compensating condenser 48, which are series resonant at the operating mean frequency, is provided, and by means thereof there is produced in the circuit an additional resistance adjustable in amount and proportion to the square of the frequency change thereby to compensate for the residual resistive effect. The principle of equal reciprocities, discussed in connection with Figure 1, c and d can also be applied to the compensating network and accordingly a resistor connected in series to an antiresonant circuit, composed of an inductance and a capacitance in parallel, would have a conductive component equal to the resistive component of the network shown in Figure 5. The adjustment of the network shown in Figure 5 is readily accomplished by first adjusting the variable resistor 46 to a medium value, without signal impulses, tuning inductance 47 and capacitance 48 to resonance with the oscillator frequency, which is shown by maximum oscillator amplitude, and then modulating the oscillations and adjusting resistor 46 until no variation of the oscillator amplitude can be observed.

According to this invention the methods herein disclosed can be applied to frequency modulations of telegraph signals as well as of telephone signals. This may be illustrated by oscillators utilizing crystal control, which in many respects are equivalent to free oscillators.

A crystal itself without its mounting is electrically equivalent to a capacity shunted by a sharply series resonant circuit consisting of a very small capacity, a very high inductance and a relatively small damping resistance. The mounting, and external circuit connections introduce both series and parallel capacity, so that the crystal in its mounting, and connected to the grid of a "tuned plate" oscillator circuit, can be illustrated by an equivalent electrical circuit according to Figure 6.

In this figure 51 is the equivalent of the mechanical resistance of the crystal, 52 is the equivalent of the mechanical inductance of the crystal, 53 is the equivalent of the mechanical capacitance of the crystal, 53a is the electrical capacitance of the crystal, 54 is the series electrical capacitance, 55 is the parallel electrical capacitance and 56 is the negative feed-back resistance introduced by the tube. It is known that the frequency of crystal oscillators can be affected by varying the distance between the crystal and its mounting plate and frequency modulating circuits based on this principle have been proposed. However, while these circuits modulate the frequency they also affect the amplitude of modulation, in accordance with the above explained principle that in every circuit containing reactances and resistances a change of one of the reactances always produces a resistive effect.

20 In Figure 7, there is shown a circuit arrangement for frequency modulated radio telegraphy with a crystal controlled oscillator. As here shown the arrangement comprises an oscillator tube 61, a plate battery 62, a filament battery 63, a grid bias battery 64, a plate tuning coil 65, a plate tuning condenser 66, a radio frequency choke coil 67 constituting a direct current bypass in the grid circuit, crystal mounting plates 68 and 69, an oscillating crystal 70, a grounding condenser 71, a modulating condenser 72, a modulating resistor 73 and a telegraph key or relay 74. This circuit with the exception of the grounding and modulating condensers, the modulating resistor, and the telegraph key is a standard crystal oscillator circuit well known to the art and requires no additional explanation. The series ground capacity 71 is introduced in order to provide a circuit reactance external to the crystal impedance, which may be influenced by other external means, namely the series resistance and capacity 73 and 72 respectively. The telegraph key may be connected across resistor 73, across the capacity 72 or across parts of either or both of them. In any case, the relative impedances of condenser 72 and resistor 73, with respect to each other and to the other circuit impedances, can be so adjusted that by short-circuiting part of condenser 72 or resistor 73, or parts, of both of them, only the tuning reactance of the equivalent resonant circuit is affected and not the resistance.

55 In Figure 8 there is shown an arrangement for modulating a telegraph transmitter by moving the crystal mounting plate in a manner similar to that known in the art but with added means provided for eliminating the undesired amplitude modulation. As here shown, the arrangement comprises an oscillator tube 81, a plate battery 82, a filament battery 83, grid bias battery 84, plate tuning coil 85, plate tuning condenser 86, radio frequency choke coil 87, constituting a direct current bypass in the grid circuit, crystal mounting plates 88 and 89, oscillating crystal 90, and an adjustable capacitive plate 91 secured to the mounting plate 88 by the nuts 92 and 93. This oscillator is modulated by moving the upper mounting plate 88 upwardly or downwardly by a telegraph key directly, or indirectly by a telegraph relay. The method of varying the circuit resistance by capacity changes is twice used in this arrangement. Increasing the distance between mounting plate 88 and crystal 90 increases the oscillator frequency but also the effective circuit resistance so that a decrease in amplitude would result. In the circuit illustrated by Fig-

ure 6 a decrease in capacity 54 is the equivalent of this movement. This movement of plate 88 also decreases the capacity between said plate and the auxiliary plate 91, which is equivalent in Figure 6 to a reduction of capacity 55. This will also increase the oscillator frequency but will reduce the equivalent circuit resistance. By adjusting the original distance between plates 88 and 91, this reduction of resistance may be made to compensate for the increase caused by the gap between crystal 90 and the plate 91, thus producing pure frequency modulation without amplitude change. This can be understood more clearly by reference to Fig. 6, described above. In Fig. 8, the capacity of the gap between plate 88 and crystal 90 is the equivalent of capacity 54 in Fig. 6, and the capacity between plates 88 and 91 corresponds to a part of capacity 55 in Fig. 6. Now, it is a fundamental principle of oscillator circuits that their amplitude is stable only when the positive resistance of the working circuit is equal to the negative resistance supplied by the regenerating circuit. A preponderance of positive resistance will decrease the amplitude, a preponderance of negative resistance will increase the amplitude until the non-linearity of tube characteristic, etc., reestablishes the balance at a different level. Now, if in a circuit of the type shown in Fig. 8 we attempt to vary the resonance frequency by a change in the series capacity 54 alone, this cannot be achieved without affecting the circuit resistance and thereby producing amplitude changes. Therefore, we apply the above stated principle a second time by simultaneously varying a second capacity, to wit, 55. A variation of 55 will affect the resistive component of the total net work consisting of parts 51 to 55. An increase of 54 will tend to increase the resistive component of net work impedance, whereas an increase of 55 will tend to decrease said component. If, by correct placing of 91 relative to 88, we make said decrease equal to said increase of resistive component, the result is a variation of the reactive component only of the combined network impedance; therefore, a variation of oscillating frequency only, without change in amplitude.

40 While I have shown and described several embodiments and applications of my invention it will be understood that the invention may be otherwise embodied and applied as will be understood by those skilled in the art. Therefore, I do not wish to be limited to the present disclosure except as may be required by the appended claims and the prior art.

50 Having thus described the invention, what I claim is:

1. The method of varying the resistive component of the total effective circuit impedance of an alternating current circuit containing a component which is predominantly resistive and a component which is predominantly reactive which comprises varying the value of said predominantly reactive component in such a manner that the reactive component of the total effective circuit impedance remains substantially constant while the resistive component varies.

2. The method of varying the reactive component of the total effective circuit impedance of an alternating current circuit containing a component which is predominantly resistive and a component which is predominantly reactive which comprises varying the value of said predominantly resistive component, producing variations in said reactive component, in such a

manner that the resistive component of the total effective circuit impedance remains substantially unaffected by said variation.

3. The method of modulating the frequency 5 of an electric wave in an alternating current circuit containing a component which is predominantly resistive and a component which is predominantly reactive which comprises varying the effective circuit reactance by varying the 10 value of said predominantly resistive component while maintaining the resistive component of the total effective circuit impedance substantially constant.

4. The method of modulating the frequency of 15 an electric wave in a radio frequency circuit having resistive and reactive components which comprises reactively coupling said circuit to the plate circuit of a thermionic tube and varying said reactive component by varying the plate resistance of said tube while maintaining the resistive component of the total effective circuit impedance substantially constant.

5. The method of modulating the frequency of 20 an electric wave in a radio frequency circuit having resistive and reactive components which comprises reactively coupling said circuit to the plate circuit of a thermionic tube, and varying said reactive component by varying the plate resistance of the tube by varying the voltage impressed on 25 the grid of said tube while maintaining the resistive component of the total effective circuit impedance substantially constant.

6. The method of modulating the frequency of 30 an electric wave in a radio frequency alternating current circuit which comprises reactively coupling said circuit to the plate circuit of a thermionic tube, varying the resistance of said plate circuit to thereby vary the reactance of said radio frequency circuit, and introducing into said circuit a resistive effect to neutralize the resistive 35 effect produced by varying the resistance of said plate circuit.

7. The method of modulating the frequency of 40 an electric wave in an alternating current circuit containing reactive circuit elements which comprises producing frequency changes by varying certain of said reactive circuit elements thereby producing an incidental resistive effect, and neutralizing said incidental resistive effect by simultaneously varying other of said reactive circuit 45 elements to produce a resistive effect approximately equal to and opposite to said incidental resistive effect.

8. The method of modulating the frequency of 50 an electric wave in a radio frequency circuit having resistive and reactive components which comprises reactively coupling said circuit to the plate circuit of a modulator tube, and varying said reactive component by varying the plate circuit resistance of said tube in accordance with signal 55 controlled voltages impressed on the grid of said modulator tube while maintaining the resistive component of the total effective circuit impedance substantially constant.

65 9. In combination a modulator circuit including a thermionic modulator tube, a grid circuit, and a plate circuit; a radio frequency circuit including a thermionic oscillator tube, a grid circuit and a plate circuit, and a coupling between the 70 plate circuit of said modulator tube and the grid circuit of said oscillator comprising a reactance the impedance of which at the oscillator frequency approximately equals the plate resistance of said modulator tube.

75 10. In combination a modulator circuit in-

cluding a thermionic modulator tube, a grid circuit, and a plate circuit; a radio frequency circuit including a thermionic oscillator tube, a grid circuit and a plate circuit, and a coupling between the plate circuit of said modulator tube, the grid circuit of said oscillator comprising a reactance the impedance of which at the oscillator frequency approximately equals the plate resistance of said modulator tube, and a resonant network connected to said radio frequency circuit for neutralizing the resistive effect produced therein by changes in the plate resistance of the modulator tube. 10

11. In combination a modulator circuit including a thermionic modulator tube, a grid circuit, and a plate circuit; a radio frequency circuit including a thermionic oscillator tube, a grid circuit and a plate circuit, and a coupling between the plate circuit of said modulator tube and the grid circuit of said oscillator comprising a reactance the impedance of which at the oscillator frequency approximately equals the plate resistance of said modulator tube and means for preventing amplitude variations in said radio frequency circuit. 15

12. In combination a modulator circuit including a thermionic modulator tube, a grid circuit, and a plate circuit; a radio frequency circuit including a thermionic oscillator tube, a grid circuit and a plate circuit, and a coupling between the plate circuit of said modulator tube and the grid circuit of said oscillator comprising a reactance the impedance of which at the oscillator frequency approximately equals the plate resistance of said modulator tube, and means for introducing into said radio frequency circuit a resistive effect to neutralize the resistive effect produced therein by changes in the plate resistance of said modulator tube. 20

13. An oscillator circuit, a thermionic tube having a plate circuit and a grid circuit, a reactance coupling between the oscillator circuit and said plate circuit, means for varying the resistance of said plate circuit, and means for preventing amplitude variations of the currents flowing in 45 said oscillator circuit due to changes in said plate circuit resistance including means for compensating for said resistance changes.

14. A radio telephone circuit comprising a modulator tube circuit having grid and plate circuits, a micro-phone circuit inductively coupled to said grid circuit, a radio frequency oscillator circuit reactively coupled to said plate circuit, whereby changes in the plate circuit resistance of said modulator tube circuit produced in accordance with voltage variations on said grid cause reactance changes in said oscillator circuit, and means for preventing amplitude variations in said oscillator circuit comprising means for compensating for resistance variations in 60 said oscillator circuit. 50

15. A crystal controlled oscillator having means for varying the frequency comprising a crystal, relatively movable mounting plates therefor, and an auxiliary plate adjustable to prevent changes 65 in amplitude due to relative movement of said mounting plates.

16. In an alternating current circuit having a resistive component and a reactive component, the method which comprises varying the value 70 of one of said components by varying the other component in such a manner that the component of the total effective circuit impedance similar to said other component remains substantially constant. 75

17. The method of modulating the frequency of the electric wave in an alternating current circuit containing a component which is predominantly resistive and a component which is predominantly reactive which comprises varying the effective circuit reactance by varying the value of said predominantly resistive component while maintaining the resistive component of the total effective circuit impedance substantially constant.

18. In combination a modulator circuit including a thermionic modulator tube, a grid circuit, and a plate circuit; a radio frequency cir-

cuit including a thermionic oscillator tube, a grid circuit and a plate circuit, and a coupling between the plate circuit of said modulator tube, the grid circuit of said oscillator comprising a reactance the impedance of which at the oscillator frequency approximately equals the plate resistance of said modulator tube, and a resonant network including a variable resistance connected to said radio frequency circuit for neutralizing the resistive effect produced therein by changes in the plate resistance of the modulator tube.

CARL FICHANDLER.
